Primary Examiner — Jonathan J Han*Assistant Examiner* — Caitlin MacKenzie Williams(74) Attorney, Agent, or Firm — Banner & Witcoff, Ltd.(57) CLAIM

The ornamental design for a shoe as shown and described.

DESCRIPTION

FIG. 1 is a side view of a shoe showing my new design;

FIG. 2 is a front perspective view thereof;

FIG. 3 is a front view thereof;

FIG. 4 is an opposite side front perspective view thereof;

FIG. 5 is an opposite side view thereof; and,

FIG. 6 is a top view thereof.

The broken line immediately adjacent to and surrounding the photographic area defines the peripheral bounds of the claimed design and forms no part thereof. The design is directed to the three-dimensional shape and configuration of the raised ribs and the spacing therebetween on a curved toe box of a shoe as represented in the photographic region as shown in the figures. Any surface ornamentation or lack thereof, forms no part of the claimed design. The broken lines depicting the remainder of the shoe form no part of the claimed design.
